Filed Mar. 6, 1967, Ser. No. 6,057

Term of patent 14 years

(Cl. D22—99)

FIGURE 1 is a front elevation of a riot shield or similar article showing my new design wherein the side edges or flanges are rearwardly inclined and wherein the arm loop is padded.

FIGURE 2 is a rear elevation of the shield shown in FIGURE 1.

FIGURE 3 is a right side elevation of the shield shown in FIGURE 1.

FIGURE 4 is a top plan view of the shield shown in FIGURE 1.

FIGURE 5 is a fragmentary sectional view of the shield shown in FIGURE 1, taken along the line 5—5 of FIGURE 1 and drawn on an enlarged scale.

FIGURE 6 is a rear elevation of a modified form of the riot shield or similar article shown in FIGURE 1 wherein the side edges or flanges are forwardly inclined and wherein two grasping handles are provided.

FIGURE 7 is a front elevation of the shield shown in FIGURE 6.

FIGURE 8 is a right side elevation of the shield shown in FIGURE 6.

FIGURE 9 is a top plan view of the shield shown in FIGURE 6.

FIGURE 10 is a fragmentary sectional view of the shield shown in FIGURE 6 taken along the line 10—10 of FIGURE 6 and drawn on an enlarged scale.

I claim:

The ornamental design for a riot shield or similar article, substantially as shown and described.
